UNITED STATES PATENT OFFICE.

ROBERT GRUNDY BROOKE, OF MACCLESFIELD, ENGLAND, ASSIGNOR TO HOLDEN & BROOKE, LIMITED, OF MANCHESTER, ENGLAND.

STEAM INJECTOR.

Application filed January 15, 1927. Serial No. 161,425.

This invention relates to injectors in which use is made of exhaust steam. In some cases the pressure of the exhaust steam used varies considerably, and may prove inconvenient. 5 For instance, on a locomotive, the pressure of the exhaust in the pipe supplying the injector may be anything from 0 to say 20 lbs. per square inch or more, above atmosphere and if this variation of pressure reaches the injector, 10 the latter requires regulating by hand to meet such variation, thus necessitating care and attention on the part of the driver.

One object of the present invention is to regulate automatically the pressure of the 15 exhaust steam when entering the injector irrespective of the pressure of the exhaust steam in the supply pipe therefor.

An exhaust injector will work with steam at from 0 to say 7 lbs. pressure without regulation and a further object of the invention is to provide robust means which will regulate the pressure in the injector to values well within this range when the pressure of the exhaust steam in the supply pipe necessitates 25 this.

Another object of the invention is to provide, for the regulation of exhaust steam pressure in an injector, valve means adapted, in cases where live steam replaces exhaust steam 30 for feeding the injector, to prevent escape of live steam, by way of the supply pipe, for the exhaust steam.

These and other minor objects will readily appear from the description now about to be 35 given with the aid of the accompanying drawings in which Fig. 1 is a side elevation and Fig. 2 a plan, each with parts in section, of an attachment to the body of an exhaust injector fitted with the regulating means. Fig. 40 3 is an elevation at right angles to Fig. 1.

As here shown the exhaust steam supply pipe 1 is connected to the injector body 2, to the rear of a valve 3 which separates the pipe 1 from a chamber 4 at what for convenience 45 may be termed the regulated pressure side of the valve. In the example, a butterfly valve is shown, though a valve of any other suitable balanced type may be employed. The valve 3 is actuated by an external lever 5 secured to the spindle 6 which is brought to the outside of the casing through a packed gland 7. To the lever 5 is connected a tension spring 8 tending normally to hold the valve 3 open. The tension of this spring 8 can be adjusted 50 in any suitable way such as by turning a nut 9

upon a screw threaded eye bolt 10. The lever 5 is connected by a link 11 to a piston 12 constituting with the cylinder 13 and a closure 14, a chamber 15 which communicates with the exhaust steam chamber 4 by a passage 16. 60

The injector for use in connection with my invention is intended to be equipped with a change-over valve such as is illustrated in the specification of Letters Patent No. 1,706,346 so that when, as on a locomotive, the engine is 65 not under steam and there is no exhaust to work the injector, live steam is used to take the place of the exhaust, the valve referred to automatically establishes the live 70 steam supply as an auxiliary as soon as the exhaust supply stops. Thus whilst 17 represents the passage intended to be connected to the branch 32 of the change-over valve of the said earlier application and so conduct live steam to the live steam spindle 75 means supplied through the passage 18, 19 similarly represents the passage intended to be connected to the branch 33 of the change-over valve whereby live steam is, when desired, conducted to the chamber 4. In such an 80 instance, a non-return valve 20 is employed to permit steam to flow from the chamber 4 through passage 16 into the chamber 15 but not in the contrary direction and a passage 21, intended to be connected as to the pipe 26 85 of the arrangement of the earlier application referred to serves to conduct live steam to the chamber 15 as and for the purpose to be hereinafter described.

Broadly the action is as follows:—Assuming exhaust steam to be available and the valve 3 to be open, then a portion of such exhaust steam will pass from the pipe 1 to chamber 4, and thence by passage 16 to chamber 15, opening the valve 20 if employed. As the pressure in chamber 4 tends to rise so will it also tend to rise in chamber 15 where, acting upon the piston 12, it tends to overcome the pull of the spring 8 thereby gradually closing the valve 3 as the pressure in the pipe 1 rises. The regulation of the pressure in chamber 4 will only be an approximate one but the rise in it due to increasing pressure in the pipe 1 will be limited so as to obviate independent regulation of the injector. 95

When, as in the more specific example illustrated, live steam is introduced at 19 as an auxiliary to exhaust steam when the latter is not available, a portion of such live steam is at the same time conducted through passage 100 105 110

21 directly into the chamber 15. This steam being unable, because of valve 20, to find its way out of the chamber 15 acts on the piston 12 in such a manner as to close the valve 3 to the fullest extent possible thus permitting no or next to no steam to pass from chamber 4 to the pipe 1. It is of course understood that the live steam supplied to the chamber 4 as an auxiliary source is reduced to the quantity 10 of pressure required, no regulation being necessary.

What I claim is:—

1. An attachment for exhaust steam injectors comprising, in combination with a rotary valve controlling the steam inlet, spring-actuated means external to the injector body or casing connecting said valve with a fixture on said casing and tending to hold said valve open, and steam-actuated means external to said casing tending to close said valve in opposition to the spring; said steam-actuated means comprising a cylinder attached to said casing, a piston in said cylinder, a steam inlet passage leading from the interior of the casing into said cylinder, and connections 25 between said piston and valve whereby the lat-

ter is adapted to close when the pressure within the casing increases and to open when the pressure decreases.

2. An attachment for exhaust steam injectors comprising a rotary valve controlling the steam inlet; said valve being fixed on a shaft having an upstanding arm or lever on the outside of the casing, a spring connecting said lever with a fixture on the outer side of the casing and by its pull tending to open said valve, and steam-actuated means tending to close said valve in opposition to the spring; said steam-actuated means comprising a cylinder outside of the casing provided with a steam inlet passage leading from the interior of the casing, a piston in said cylinder, and a rod connecting the piston with said lever so as to adapt the piston to close the valve against the pull of the spring, whereby the pressure of the exhaust steam when entering the injector body or casing is regulated irrespective of the pressure of the exhaust steam supply therefor.

Signed at Manchester, England, this third day of January, 1927.

ROBERT GRUNDY BROOKE.
